UNITED STATES PATENT OFFICE

HOWARD R. HUGHES, OF HOUSTON, TEXAS, ASSIGNOR TO SHARP-HUGHES TOOL COMPANY, OF HOUSTON, TEXAS, A CORPORATION OF TEXAS.

RETAINING MEANS FOR ROTARY-DRILL CUTTERS.

1,174,577.

Specification of Letters Patent.

Patented Mar. 7, 1916.

Application filed February 24, 1914. Serial No. 820,678.

To all whom it may concern:

Be it known that I, HOWARD R. HUGHES, a citizen of the United States, residing at Houston, Texas, have invented a certain new 5 and useful Improvement in Retaining Means for Rotary-Drill Cutters, of which the following is a full, clear, and exact description, such as will enable others skilled in the art to which it appertains to make and use the 10 same.

This invention relates to rotary boring drills of the type in which the cutters are held in operative position on their spindles by means of retaining rings on the cutters 15 that project under laterally projecting portions on the spindles, such, for example, as in the drill shown in my prior Patent No. 979,496, dated Dec. 27, 1910. In the drill shown in the patent above-referred to the 20 retaining ring is screwed into the cutter, and the head of the drill is provided with a hole through which a tool can be inserted so as to hold the retaining ring at rest when the cutter is being screwed onto or off of 25 same.

The object of my present invention is to provide a cutter-retaining means of novel design which can be manufactured cheaply, which enables the cutter to be applied and 30 removed quickly, and which overcomes the necessity of forming a hole in the head to receive a tool for holding the retaining ring at rest when the cutter is being attached to and disconnected from same.

35 Figure 1 is a side elevational view, partly broken away, of a rotary boring drill whose cutters are held in operative position by my improved cutter-retaining means; and Fig. 2 is a sectional view taken on the line 2—2 40 of Fig. 1.

Referring to the drawings which illustrate the preferred form of my invention, A designates the head of the drill, and B designates the approximately frusto-conical-shaped cutters that are rotatably mounted on said head on spindles that are either formed integral with the head or detachably connected to the head, and which are provided with shoulders or laterally projecting 45 portions that lap over retaining rings C to which the cutters B are connected.

In the form of my invention herein illustrated the head A of the drill is provided with integral spindles 1, each of which is 50 equipped with a removable portion or bush-

ing 2 that has a reduced portion so as to form a shoulder 3 which laps over the retaining ring C that is loosely mounted on said reduced portion, but I do not wish it to be understood that my invention is limited to such a construction as my present invention relates particularly to the means for connecting the retaining ring C to its cutter. 60

Instead of screwing the retaining ring C into an internally screw-threaded bore in the base end of the cutter, as has heretofore been the general practice, the retaining rings of the drill herein shown are merely seated loosely in circular recesses formed in the base ends of the cutters, and each cutter is 70 provided with a plurality of radially-disposed, removable fastening devices, preferably hollow set screws 4, whose inner ends project into an annular groove 5 formed in the outer face of the retaining ring. The 75 cutter is provided with screw-threaded openings 6 for the retaining devices 4 which extend at approximately right angles to the spindle 1, thereby effectively holding the cutter in operative position and preventing 80 it from moving longitudinally of the spindle. 85

In a construction of the character above-described it is not necessary to form internal screw-threads on the walls of the recess or socket in the cutter which receives the retaining ring, it is not necessary to form a hole in the head of the drill to receive a tool or device for holding the retaining ring at rest while the cutter is being connected to and disconnected from same; and another 90 desirable feature of such a construction is that the cutters can be applied and removed quickly by simply manipulating the fastening devices 4 that project into the annular groove in the retaining ring. 95

Having thus described my invention, what I claim as new and desire to secure by Letters Patent is:

1. A rotary boring drill comprising a head, a cutter, a spindle on which said cutter is rotatably mounted, said spindle having a shoulder, a retaining ring arranged loosely in a recess in said cutter and rotatably mounted on said spindle under said shoulder, and removable fastening devices 100 on the cutter that project into an annular groove formed in said retaining ring, and thus prevent the cutter from moving longitudinally of the spindle. 105

2. In a rotary boring drill, an approxi- 110

mately frusto-conical-shaped cutter having a recess formed in the base end of same, a retaining ring loosely mounted in said recess, a spindle for the cutter fitting loosely inside of said ring and having a laterally projecting portion that laps over said ring and prevents it from moving longitudinally of the spindle, and set screws in said cutter arranged at approximately right angles to the spindle and projecting into an annular

groove formed in said retaining ring so as to prevent the cutter from moving longitudinally of the spindle.

In testimony whereof I hereunto affix my signature in the presence of two witnesses, 15 this 13th day of February 1914.

HOWARD R. HUGHES.
